UNITED STATES PATENT OFFICE.

JOSEPH DEUBEL, OF CLIFTON, NEW JERSEY.

AMUSEMENT TARGET DEVICE.

Application filed September 25, 1922. Serial No. 590,308.

To all whom it may concern:

Be it known that I, JOSEPH DEUBEL, a citizen of the United States, and a resident of Clifton, in the county of Passaic and State of New Jersey, have invented a new and useful Amusement Target Device, of which the following is a specification.

The object of my invention is to afford original and interesting amateur target apparatus for amusement purposes in which a certain degree of skill is required on the part of the player in effecting initial adjustment of parts in so far as aim of the projectile, as related to the target, is concerned, but which otherwise is practically automatic in operation, including the retractile movement of the projectile and its mount as hereinafter exemplified; the invention consisting essentially in the specific construction, combination, and arrangement of parts and appurtenances described and claimed, and distinctive features being the projectile mount and its sighting means; the means for automatically re-setting the operative parts; and certain other incidental adjunctive accessories mentioned in due course, and all as hereinafter fully set forth.

In the accompanying drawings, I illustrate a practical embodiment of the essential features of my invention, although I do not limit myself to the identical form and construction of parts shown, as it is obvious that changes in minor details may be resorted to and equivalent mechanical expedients, may be substituted, with like result, and without departing from the spirit and intent of my invention in this respect.

With this understanding,

Fig. 1, represents a side elevation of my amusement device; and

Fig. 2, a plan thereof;

Fig. 3, is a vertical sectional elevation of the rear portion of the apparatus, taken upon plane of line 3—3, Fig. 1, but on a larger scale;

Fig. 4, is a detail view of one of the standards, indicating in dotted lines the depressed position of the projectile mount;

Fig. 5, is a detail view of the retractile trip device at the rear end of the projectile carriage range track;

Fig. 6, is a section taken upon plane of line 6—6, Fig. 5;

Fig. 7, is a section taken upon plane of line 7—7, Fig. 1, but upon a larger scale, 55 showing a front elevation of the projectile carriage, etc.,

Fig. 8, is a sectional elevation taken upon plane of line 8—8, Fig. 7;

Fig. 9, is a horizontal sectional elevation 60 taken upon plane of line 9—9, Fig. 8;

Fig. 10, is a detail view of the trigger device;

Fig. 11, is a diagram showing, in horizontal projection, the means for the lateral adjustment of the projectile; 65

Fig. 12, is a similar diagrammatic view taken at right angles to Fig. 11;

Fig. 13, is a view similar to Fig. 1, showing the relative position of the parts when 70 the range tracks are depressed;

Fig. 14, is a sectional detail of a bull's eye pin adapted for use as a circuit closer;

Fig. 15, is a detail of the shooting trigger mount; 75

Fig. 16, is a side elevation showing the projectile carriage at the inner end of the range tracks, as positioned when the projectile misses the bull's eye;

Fig. 17, is a partial top view of the projectile carriage, etc, positioned as shown in Fig. 16; 80

Fig. 18, is a view like unto Fig. 3, showing the range tracks lowered.

T, represents a fixed target, the essential 85 feature of which is the "bull's eye" pin b, which is movably mounted in the centre of said target board T, the object of the play being to so aim the projectile P, as to cause it to strike said bull's eye pin b, and drive it 90 into contact with the circuit closing means c, forming part of the electric circuit C, in which is interposed an electric light bulb c', bell, or other device for announcing the fact that a "bull's eye" has been scored by the 95 player, if successful. Unless the bull's eye peg b, is struck there is no signal, and no count. In order to effect the closure of electric circuit by the "bull's eye" pin b, is struck by the projectile P, said pin b, is 100 metallic, in whole or in part; or otherwise may obviously be made to close a switch or equivalent mechanical expedient as well known in the electrical art.

Fig. 14, shows a sectional detail of a bull's 105 eye pin b, suitable for use in conjunction

with my amusement target device, in which the tubular body b' , of the pin is formed of insulating material, with a metallic tip b^2 , to act as the circuit closer, the bull's eye itself consisting of the head disc b^3 , of a screw engaging with the aforesaid tubular body b' and a spiral spring b^4 , being interposed between said disc b^3 , and the supporting standard d , on which the bull's eye pin b , is mounted,—said spring tending constantly to hold the pin b , in retracted position with the stop b^5 , resting against the rear side of said support d , and with the circuit-closing tip b^2 , out of contactual engagement with the circuit closing means c , as in Fig. 1. When the projectile P , strikes the disc b^3 , of the bull's eye pin b , it exerts sufficient pressure thereon, not only to close the circuit C , but also to maintain it closed until the projectile P , is retracted, as herein after set forth.

What may be designated as the range tracks r , r , are pivotally supported at their rear extremities adjacent to, in front of, and below the target T , as indicated at r^x , r^y , Figs. 1, 2 and 13, of the drawings. These range tracks r , r , are parallel, but the central vertical or medial plane therebetween is not in alignment with the bull's eye b , as will be seen more particularly by reference to Fig. 2, the object of this arrangement of parts being to render the aim adjustment of the projectile P , in order to attain a score, more difficult than if the said range tracks r , r , were equidistant from, and as related to, the prescribed position of said bull's eye b .

The range tracks r , r , are connected rigidly together at their forward extremities by inturned transverse extensions r' , r' , united medially by the tines h , h , of the handle H , interposed between them, as will be understood by reference more particularly to Figs. 10 and 15 of the drawings. A fulcrum rod f , extends through the said tines h , h , of the handle H , upon which rod f , is pivotally supported the latch trigger t , formed with the latch shoulder t' , and with the finger rest t^2 ,—a spring h' , on the handle H , tending constantly to rock the latch trigger t , upward so that its latch shoulder t' , will engage with a shoulder k , on the tongue k' , of the projectile carriage K , when the latter is in retracted position as in Figs. 1 and 13.

The carriage K , is mounted upon flanged wheels, w , w , the axles of which w' , w' , are journalled in bearing plates k^6 , k^7 , formed with bottom flanges k^8 , k^9 , which extend under the lower edges of the range tracks r , r , as shown more particularly in Figs. 7 and 8, of the drawings, so as to prevent derailment.

On the platform k^4 , of the carriage K , is rigidly secured the rectangular box k^5

within which is positioned the slidable adjustment block A , upon which the projectile P , is mounted.

The projectile P , as shown in the drawings, may consist of a miniature representation of a gun, for which may obviously be substituted, with like effect, a representation of an arrow, or any other desired or preferred form of protuberant missile adapted to contact with the bull's eye disc b^3 , of the pin b , if properly aimed thereat.

The projectile P , is affixed to the upper extremity of a substantially vertical elevation-screw V , which engages normally with a semi-circular female screw thread a , formed for the purpose in the adjustment block A , such engagement being shown more particularly in Figs. 8, 9, and 11, of the drawings, and said female screw thread a , being positioned at the forward end of an elongated slot a' , through which said elevation-screw V , passes. The lower portion of said elevation screw also passes through an elongate transverse slot k^6 , in the bottom of the box k^5 , and the platform k^4 , of the carriage K , said slot k^6 , being shown in cross section in Fig. 8, and indicated by dotted lines in Figs. 9 and 11, of the drawings. The rear portion of the projectile P , rests between side guides a^2 , a^2 , on the block A , which maintain the alignment thereof, as related to the centre of said adjustment block A . The elevation-screw V , is turned on its longitudinal axis by means of a manipulative head v , or equivalent mechanical expedient.

The said adjustment block A , is laterally movable in either direction upon the platform k^4 , of the carriage K , and within the box k^5 , so as to vary the horizontal alignment of the projectile P , as related to the target T , by means of what may be designated as the horizon screw I , formed with journals i , i , at its opposite extremities, which rest in bearings in the side walls of the box k^5 , as shown more particularly in Fig. 9, of the drawings,—said journals being provided with manipulative heads i' , i'' , or other mechanical expedients by which the horizon-screw I , may be turned on its longitudinal axis.

The medial portion of said horizon-screw I , is formed with a male screw thread i^2 , for engagement with a semicircular female screw thread a^3 , forming one end wall of an elongate slot a^4 , extending transversely through the adjustment block A , as also shown more particularly in Fig. 9, of the drawings. Centralizing springs d , d , are positioned on the ends of the horizon screw I , and interposed between the adjustment block A , and the side walls of the box k^5 ; and a bow, or other form of spring e , is interposed between the forward side of said adjustment block A , and the forward side of the box k^5 , and tends con-

stantly to hold said adjustment block A, in retracted normal position, with its female screw or nut threads a , and a^3 , in engagement with the male screw threads V, and i^2 , 5 as hereinbefore set forth.

The range tracks r , r , are sustained in elevated inclination by means of a pawl q , forming one arm of the rock lever Q, fulcrumed on a bracket s, on one of the standards S, S, 10 at the forward or firing end of the apparatus, the other arm q' , of said rock lever Q, being connected with a retractile spring q^2 , which tends constantly to hold the pawl arm q , of said rock lever Q, against a stop s' , on the 15 standard, in which position the nose of the pawl arm q , protrudes on the inner side of the standard S, sufficiently to afford a support for the adjacent range track r , as shown in Figs. 3 and 18, of the drawings. Hence 20 one of the functions of the retractile spring q^2 , is to lock the range tracks r , r , in elevated inclination, as in Figs. 1, 2, 3, and 16.

To the outer arm q' , of the rock lever Q, is also attached a flexible cord, chain, or other 25 form of ligature q^3 , which passes over an idler pulley s^2 , and extends to, and is secured to, the arm u , of a trip slide U, positioned in a longitudinal slot r^2 , at the inner end of one of the range tracks adjacent to the pivotal 30 support r^x , thereof. The ligature q^3 , being taut, and the arm u , being rigidly attached to the slide U, the retractile spring q^2 , tends constantly to hold the trip slide U, against the forward end wall of the slot r^2 , as shown 35 in Figs. 1, 2, and 5. On the inner side of the range track r , the trip slide U, is provided with a stud or protuberance on which may be mounted a roller u^2 , for contactual engagement with a fixed part of the projectile carriage K, as for instance a trip arm k^x , protuberant from the front edge of the platform k^4 , of the carriage K. If this strip arm k^x , or equivalent fixed part of the carriage K, contacts with the roller u^2 , upon the 40 trip slide U, at the completion of the descent of the said carriage on the range tracks r , r , it causes the trip slide U, acting through the ligature q^3 , to rock the lever Q, against the resistance of the retractile spring q^2 , thereof, 45 50 withdrawing the pawl arm q , from the support of the range track r , on that side of the track, and allowing the latter to fall to its lowest position, as in Figs. 13 and 18, buffer springs s^2 , s^2 , being provided to receive and 55 control the descent of said range tracks r , r , and prevent jar or injury to the parts involved.

My amusement target apparatus being thus combined and installed substantially as hereinbefore set forth, is operated in the following manner, presuming the range tracks r , r , to be in inclined elevated position, and the carriage K, held at the top of the incline by means of the latch trigger t, as in Figs. 1 60 and 2.

The sighting or aim of the projectile P, as related to the bull's eye disc b^3 , is effected, according to the judgment of the player, by means of the elevation screw V, and the horizon-screw I, taking into consideration 70

the pitch of the range tracks r , r , and their lack of alignment with relation to the said bull's eye disc b^3 . Upon the release of the carriage K, by the withdrawal of the latch t, from engagement with the tongue k' , of the carriage K, the latter travels down the incline of the range tracks r , r . If the aim is correct, the projectile P, strikes the bull's eye disc b^3 , forcing the pin b, inward and closing the electric circuit C, or otherwise 80 actuating a suitable signal, as the case may be. The contacting of the projectile P, with the bull's eye disc and pin prevents the trip arm k^x , or equivalent fixed part of the car K, from contacting with the trip slide U, and 85 hence holds the parts temporarily in record position, until re-set manually. If, however, as is more frequently the case, a "bull's eye" is not made, the carriage K, proceeds 90 until the projectile P, impinges against the target plate T, as shown in Fig. 16, thereby incidentally pushing back the trip slide U, against the resistance of the retractile spring q^2 , withdrawing the pawl arm q , and allowing 95 the range tracks to descend into the position illustrated in Fig. 18, the reverse inclination of the range tracks thus effected being sufficient to cause the return of the carriage automatically to the forward end of the tracks with the carriage K, resting 100 against the standards S, S, as shown in Fig. 13. At the completion of this retractile movement of the carriage, it automatically depresses the latch t, and thereby re-locks itself to the tracks. The range tracks r , r , are 105 then re-elevated manually by means of the handle H. During this operation cam surfaces s^x , s^x , on the inner edges of the standards S, S, contact with an extension a^x , of the slidable aim adjustment block A, pushing 110 the latter back against the resistance of the spring e, and thereby releasing both the male screws V, and I, from engagement with their female nut screws a , a^3 . As a result the adjustment block A, is returned to its medial normal position by the centralizing springs d, d, and the elevation screw V, and projectile P, drop until the latter rests upon the top of the said adjustment block A. As 115 soon as the cam surfaces s^x , s^x , are passed, the spring e, re-asserts itself, and returns the adjustment block A, to normal medial position, ready for the re-sighting or aiming of the projectile P, as related to the target, 120 as hereinbefore set forth.

What I claim as my invention and desire to secure by Letters Patent is,

1. In an amusement target device of the character designated, the combination of a retractable bull's eye, parallel range tracks 130

leading thereto, releasable means for sustaining said range track in elevated inclination, a carriage mounted upon and between said range tracks, releasable means for holding said carriage in retracted position on said range tracks, a projectile mounted on said carriage, and means for raising and lowering said projectile on the carriage and adjusting it laterally thereon, substantially in the manner and for the purpose described.

2. In an amusement target device of the character designated, the combination of a retractable bull's eye adapted to close an electric circuit, said electrical circuit, a signal connected therewith, parallel range tracks leading thereto, releasable means for sustaining said range track in elevated inclination, a carriage mounted upon and between said range tracks, releasable means for holding said carriage in retracted position on said range tracks, a projectile mounted on said carriage, and means for raising and lowering said projectile on the carriage and adjusting it laterally thereon, substantially in the manner and for the purpose described.

3. In an amusement target device of the character designated, the combination of a retractable bull's eye, a signal adapted to be actuated by said bull's eye, parallel range tracks leading thereto, releasable means for sustaining said range track in elevated inclination, a carriage mounted upon and between said range tracks, releasable means for holding said carriage in retracted position on said range tracks, a projectile mounted on said carriage, and means for raising and lowering said projectile on the carriage and adjusting it laterally thereon, substantially in the manner and for the purpose described.

4. In an amusement target device of the character designated, the combination of a retractable bull's eye, parallel range tracks leading thereto, releasable means for sustaining said range tracks in elevated inclination, a carriage mounted upon and between said range tracks, releasable means for holding said carriage in retracted position, a trip arm on said carriage, a projectile mounted on said carriage, means for raising and lowering said projectile on the carriage and adjusting it laterally thereon, and means actuated by the said trip arm on the carriage for automatically effecting the lowering of the range tracks, substantially in the manner and for the purpose described.

5. In an amusement target device of the character designated, the combination of a bull's eye, parallel range tracks leading thereto, releasable means for sustaining said range tracks in elevated inclination, a carriage mounted upon and between said range tracks, a trip arm on said carriage, a projectile adjustably mounted on said carriage,

and means actuated by said trip arm on the carriage for automatically effecting the lowering of said range tracks, together with means for automatically returning the projectile to normal position on the carriage when the range tracks are elevated manually, substantially in the manner and for the purpose described.

6. In an amusement target device of the character designated, the combination of a retractable bull's eye, parallel range tracks leading thereto, releasable means for sustaining said range track in elevated inclination, a carriage mounted upon and between said range tracks, releasable means for holding said carriage in retracted position on said range tracks, a slidable adjustment block mounted on said carriage, retractile springs which tend constantly to hold said adjustable block in normal medial position, a vertical male screw engaging with a semi-circular female screw thread formed for the purpose in said adjustment block, a projectile mounted on the upper end of said vertical male screw, a horizontal male screw engaging a semi-circular female screw thread formed for the purpose in said adjustment block, elongated slots in said adjustment block which permit of the said block being moved out of engagement of said male screws substantially in the manner and for the purpose set forth.

7. In an amusement target device of the character designated, the combination of a retractable bull's eye, parallel range tracks leading thereto, releasable means for sustaining said range track in elevated inclination, a carriage mounted upon and between said range tracks, releasable means for holding said carriage in retracted position on said range tracks, a slidable adjustment block mounted upon said carriage, retractile springs which tend constantly to hold said adjustable block in normal medial position, a vertical male screw engaging with a semi-circular female screw thread formed for the purpose in said adjustment block, a projectile mounted on the upper end of said vertical male screw, a horizontal male screw engaging a semi-circular female screw thread formed for the purpose in said adjustment block, elongated slots in said adjustment block which permit of the said block being moved out of engagement of said male screws, together with means for automatically moving said adjustment block on the carriage for the purpose of returning the parts to normal positions with relation to each other, substantially in the manner and for the purpose set forth.

8. In an amusement target device of the character designated, the combination of a retractable bull's eye, parallel range tracks leading thereto, releasable means for sustaining said range tracks in elevated in-

- clination, a carriage mounted upon and between said range tracks, releasable means for holding said carriage in retracted position on said range tracks, a slidable adjustment block mounted on said carriage, retractile springs which tend constantly to hold said adjustable block in normal medial position, a vertical male screw engaging with a semi-circular female screw thread 5 formed for the purpose in said adjustment block, a projectile mounted on the upper end of said vertical male screw, a horizontal male screw engaging a semi-circular female screw thread formed for the purpose in said adjustment block, elongated slots in said adjustment block which permit of the said block being moved out of engagement of said male screws, and means for maintaining the longitudinal alignment of 10 the projectile, substantially in the manner and for the purpose set forth.
- 15 9. In an amusement target device of the
- character designated, the combination of a bull's eye, parallel range tracks leading thereto, releasable means for sustaining said range tracks in elevated inclination, a carriage mounted upon and between said range tracks, a contact trip surface on said carriage, a projectile adjustably mounted on said carriage, and means actuated by 20 said contact trip surface on the carriage for automatically effecting the lowering of said range tracks, consisting of a yieldable part positioned at the inner end of the range tracks and connected with the said releasable means for sustaining the said range tracks in elevated inclination, substantially 25 in the manner and for the purpose described.
